UNITED STATES PATENT OFFICE.

FRANK A. WHITTEN, OF DETROIT, MICHIGAN, ASSIGNOR TO GENERAL MOTORS CORPORATION, OF DETROIT, MICHIGAN, A CORPORATION OF DELAWARE.

MUFFLER.

1,422,403. Specification of Letters Patent. Patented July 11, 1922.

Application filed June 17, 1919. Serial No. 304,755.

To all whom it may concern:

Be it known that I, FRANK A. WHITTEN, a citizen of the United States, and resident of Detroit, Wayne County, State of Michigan, have invented certain new and useful improvements in Mufflers, of which the following is a specification.

My invention relates to mufflers designed for use with internal combustion engines to reduce the noise incident to the exhaust therefrom, and the object thereof is to provide a muffler of simple construction and one which may be manufactured at small cost, and which will at the same time be effective for the purpose of silencing the exhaust from the engine with which it is used.

With the above and other objects in view, my invention consists in the improved muffler illustrated in the accompanying drawings and hereinafter described, and claimed, and in such variations and modifications thereof, within the scope of the concluding claims, as will be obvious to those skilled in the art to which my invention relates.

Referring to the drawing, wherein the preferred embodiment of my invention is illustrated.

Figure 1 is a view showing my improved muffler in side elevation and as supported from a suitable support such, for example, as from the frame of a vehicle operated by an internal combustion engine;

Figure 2 is a view showing a section upon a vertical transverse plane indicated by the lines II, II, Figure 1;

Figure 3 is a view showing a section upon a vertical transverse plane indicated by the line III, III, Figure 1;

Figure 4 is a view showing a portion of the under side of the muffler;

Figure 5 is a view showing a section of a portion of the muffler at the right-hand end of Figure 1, upon a vertical plane;

Figure 6 is a view showing the left-hand end of the muffler;

Figures 7, 8 and 9 are views showing modified forms of the left-hand end of the muffler tube and the head for closing the end thereof;

Figure 10 is a view showing a modified form of supporting member for the ends of the muffler; and

Figures 11 and 12 are views showing modified forms of outlets through which the

exhaust gases escape from the muffler tube.

Referring to the drawing, the reference numeral 15 designates a tubular member or muffler tube which forms the main body portion of the muffler, and which tube is provided with two flanges or walls 16-16, extending longitudinally thereof and outwardly therefrom in a radial direction. The tube is preferably formed from comparatively thin sheet metal, and the flanges or walls 16 are preferably provided by folding the side edges of the sheet of metal from which the muffler tube is formed, as clearly shown in the cross sectional views, Figures 2 and 3, and bending the folded portions so as to cause the resulting flanges to extend outwardly from the peripheral wall of the finished tube. The walls or flanges extend throughout the entire length of the plate or sheet from which the muffler tube is formed, and throughout the entire length of the resulting tubular member; and said flanges are spaced apart from one another to thereby provide a passage extending longitudinally of the tubular member, and through which the exhaust gases may escape gradually and with comparatively little noise.

These outwardly extending flanges may be parallel, as shown in Figures 1 to 6, in which case the passage between them is of uniform width throughout, or they may flare outwardly, as shown at 17 in Figures 11 and 12, in which last mentioned case the opening between the flanges becomes wider as said flanges recede from the main body or peripheral wall of the muffler tube, thereby providing an expanding nozzle through which the exhaust gases escape, as will be understood.

The flanges above referred to are preferably secured together at intervals by means of rivets 18 spaced apart from one another and which extend through suitable spacers 19 placed between the flanges, whereby the said flanges are held in proper positions to provide an outlet slot or opening of substantially equal width throughout, and a stiff and comparatively rigid tubular member is provided.

The tubular member 15 is supported from a suitable support by means of supporting members located one at each end thereof, and which supporting members are shown in Figures 1 to 6 as comprising brackets 20

3018401 MUFFLER having holes at their lower ends through which supporting bolts 21 extend. The reference numerals 22 designate semi-circular clamps arranged in pairs at each end of the tube 15, said clamps having ears 23 at their upper and lower ends. The supporting bolts 21 pass through the holes in the upper ears 23 and thus support the clamps and the muffler as a whole from the brackets 20; and clamping bolts 24 extend through the ears at the lower ends of each pair of semi-circular clamps and serve to draw the lower ends of said clamps together and secure the muffler tube in place.

150 The supporting members above described are obviously made up each of three pieces. In the form of muffler support illustrated in Figure 10, however, the supporting member is made up of two pieces only; the main portion 25, which is secured to the frame member 26 having a curved lower portion of such a size as to embrace half of the muffler tube, while a yoke 27, curved and semi-circular in form and adapted to embrace the remaining portion of the periphery of the muffler tube is secured to the said main supporting member by bolts 28 at its ends.

155 The supporting members thus provided are referred to as collapsible because of the fact that the action of the clamping bolts 24 draws the lower ends of the clamps 22 toward one another, and forces their inner surfaces into contact with the peripheral wall of the muffler tube at the ends thereof and thus holds the tubular member 15 in place, in the form of my invention illustrated in Figure 1 to 6; and a similar clamping action obviously results when the bolts 28 of the form of my invention illustrated in Figure 10 are tightened.

160 The depending walls or flanges 16 of the tubular member 15 are provided with semi-circular recesses adjacent the ends of the tube and within which recesses the clamping bolts 24 lie when the parts are assembled, which recesses serve to position the lower ends of the semi-circular clamps and the bolts 24 properly before the tightening of the bolts to secure the parts in their final positions; as well also as to prevent relative movement between the clamps and the tube if the clamping bolts are not tightened sufficiently to prevent such movement by the resulting engagement between the inner surfaces of the clamps and the exterior surface of the muffler tube.

165 The reference numeral 29 designates an exhaust conduit leading from the engine, and which obviously forms an inlet conduit through which the exhaust gases flow into the interior of the muffler tube 15, the end of said conduit 29 fitting within the right-hand end of the said tube as best shown in Figures 5 and 10. It therefore follows that 65 the act of tightening the semi-circular clamps

22, or the yoke 27, will force the right-hand end of the muffler tube into firm engagement with the end of the conduit 29, and thereby hold the parts in permanent fixed relation relative one to the other.

170 The left-hand end of the muffler tube 15 is shown in Figures 1, 3 and 6 as closed by a head 30, which head is likewise held in place within the left-hand end of the muffler tube by the clamping action which follows the drawing together of the lower ends of the semi-circular clamps 22 at the left-hand end of the tube by the clamping bolt 24. The left-hand pair of clamping members will also preferably be provided each with a lug 80 31, which lugs overlie the end wall of the head 30 and serve to more effectively prevent displacement of said head if, for example, the clamps at that end of the tube are not sufficiently tightened, or if, they should 85 become loose during the use of the device. Figures 7, 8 and 9 show the tube end closing head 32 as made from a sheet or thin plate metal stamping the periphery of which is turned up to form a flange, and as held in place within the end of the tube by spot-welding the flange and tube wall together at 33 in Figure 7, and by rivets 34 in Figure 8; the holding means being preferably upon the upper side of the tube and opposite the passage leading therefrom, so that the sides thereof may be forced against the peripheral wall of the head when the bolts 24 or 28 are tightened, as will be understood.

180 Figure 12 shows a muffler in which the opening extending along the muffler tube 15 is wider than in the forms of my invention shown in the other figures, and as having a spreader 35 extending longitudinally of the opening and secured in place by longer 105 rivets 36 extending through the flanges 17 and the said spreader; the spreader being made from a folded strip of sheet metal and spaced apart from the adjacent flanges 17 by spacers 37. In this form of muffler the escaping exhaust gases are divided into two streams by the spreader, which streams are directed away one from the other by the flaring walls 17 of the tube and the similarly shaped side walls of the spreader and between each two adjacent walls an expanding 115 outlet or nozzle is secured, thereby further reducing the noise incident to the exhaust gases escaping into the atmosphere.

120 Having thus described and explained my invention, I claim and desire to secure by Letters Patent:

1. A muffler consisting of a tubular member of substantially uniform area throughout its length and having two flanges extending outwardly from its periphery and longitudinally thereof and throughout the length of the muffler, and which flanges are spaced apart from one another to thereby provide an outlet passage between them.

2. A muffler consisting of a tubular member circular in cross-section and of substantially uniform area throughout its length, and having two flanges extending outwardly from its periphery, and longitudinally throughout the entire length thereof, and which flanges are spaced apart from one another to thereby provide an outlet passage between them; and a series of fastening members extending through said flanges and spaced apart from one another.

3. A muffler of the class described comprising a tubular member having two flanges extending outwardly from its periphery and longitudinally thereof, and which flanges are spaced apart from one another to thereby provide an outlet passage between them; two collapsible supporting members located one at each end of said tubular member; an inlet conduit fitting within one end of said tubular member; a head fitting within the other end of said tubular member; and means for collapsing said supporting members to thereby clamp said inlet conduit and said head in place.

4. A muffler of the class described comprising a tubular member having two flanges extending outwardly from its periphery and longitudinally thereof, and which flanges are spaced apart from one another to thereby provide an outlet passage between them; two pairs of semicircular clamps located one pair at each end of said tubular member, and which clamps are provided with oppositely disposed ears having holes through which bolts may extend; two supporting brackets the lower ends of which lie between the ears at the upper ends of each pair of clamps, and which supporting members are provided each with a hole through which the bolt at the upper end of said semi-circular clamps extends; clamping bolts extending through holes in the ears at the lower ends of said pairs of clamps; and notches provided in said flanges and within which notches said lower pair of bolts lie when the parts are assembled.

5. A muffler of the class described comprising a tubular member having two flanges extending outwardly from its periphery and longitudinally thereof, and which flanges are spaced apart from one another to thereby provide an outlet passage between them; two clamping members located one at each end of said tubular member and having oppositely disposed ears provided with holes through which clamping bolts may extend; and two supporting brackets the lower ends of which lie between the ears aforesaid, and are provided each with a hole through which a supporting bolt extending through the holes in the ears aforesaid may pass.

6. A muffler of the class described com-

prising a tubular member having two flanges extending outwardly from its periphery and longitudinally thereof, and which flanges are spaced apart from one another to thereby provide an outlet passage between them; a conduit leading into said tubular member; a head located within the end of said tubular member opposite said conduit; two semicircular clamping members engaging said tubular member adjacent said head; lugs carried by said clamping members and extending over the end wall of said head; means for securing said clamping members together; and a supporting bracket whereby said clamping members are supported.

7. A muffler of the class described comprising a tubular member having two flanges extending outwardly from its periphery and longitudinally thereof, and which flanges are spaced apart from one another to thereby provide an outlet passage between them; a conduit leading into said tubular member; a head located within one end of said tubular member; supporting means engaging said tubular member adjacent said head; and a lug carried by said supporting means and extending into a position so as to overlie the end of said head.

8. A muffler of the class described comprising a tubular member having two flanges extending outwardly from its periphery and longitudinally thereof, and which flanges are spaced apart from one another to thereby provide an outlet passage between them; a conduit leading into said tubular member; a head located within one end of said tubular member; a collapsible supporting member engaging said tubular member adjacent said head; and means for collapsing said supporting member to thereby force the wall of said tubular member against the periphery of said head.

9. A muffler of the class described comprising a tubular member having two flanges extending outwardly from its periphery and longitudinally thereof, and which flanges are spaced apart from one another to thereby provide an outlet passage between them; a conduit leading into said tubular member; a head located within one end of said tubular member; a collapsible supporting member engaging said tubular member adjacent said head; means for collapsing said supporting member to thereby force the wall of said tubular member against the periphery of said head; and means independent of the engagement between said supporting member and the periphery of said head and located opposite the outlet passage aforesaid for securing said head in place within the end of said tubular member.

In testimony whereof I affix my signature. 125
FRANK A. WHITTEN.
